TYPEWRITING MACHINE

Russell G. Thompson, West Hartford, Conn., assignor to Underwood Elliott Fisher Company, New York, N. Y., a corporation of Delaware

Application July 6, 1938, Serial No. 217,705

2 Claims. (Cl. 197—17)

This invention relates to typewriting machines and with regard to certain more specific features thereof to power-driven type actions.

The invention has for one of its objects to provide a power-driven type action which shall be simple in construction, inexpensive, easy to assemble and highly efficient in operation.

Another object of the invention is to employ a single lobe cam in the power-drive for the actuation of the type bar, thus reducing the number of delicate latch parts previously included in the complex double lobe cam power drives of prior structures, and generally rendering the machine more durable and more certain in the performance of its intended functions.

It is a further object of the invention to provide transmission connections from the power-driven actuator to the type bar, which are particularly well adapted to translate the short, substantially uniform, movement of the power-driven actuator into a forceful initial movement of the type bar from its inert position and quickly accelerate the type bar in its movement to the platen, wherefrom it returns quickly from typing or impact position to a point well out of the way of any type bars subsequently operated and thence gradually assumes a position of rest from which there is a minimum of rebound.

Other objects will be in part obvious and in part particularly pointed out as the following description of a preferred embodiment of the invention proceeds.

In the accompanying drawings:

Fig. 1 is a view in section taken fore and aft of a typewriting machine, with frame and carriage parts indicated schematically.

Fig. 2 is a sectional view showing one of the key-controlled power units.

Fig. 3 is a view in elevation of the power unit shown in Fig. 2.

Referring now more particularly to the drawings, a frame is indicated at 10. A carriage 11 is mounted thereon and has a conventional cylindrical platen 12. To accommodate the present power unit the frame 10 is provided with cross bars 13 and 14 suitably comb-slotted to receive and guide a multiplicity of actuating levers and sub-levers which later will be described in detail. The frame is provided at its forward end with upper and lower cross bars 15 and 16 respectively which are rubber-faced as indicated at 17 to contact the forward ends 18 of a multiplicity of key levers 19 which have their rear ends pivoted at 20 on a rod extending

from one side frame to the other. The key levers 19 are provided with keys 21.

The power-drive in the embodiment shown is a rubber-covered roller 22 driven by an electric motor (not shown). It will be obvious, however, that the invention, in certain of its aspects, contemplates the use of other power drives such, for example, as the toothed roller and pawl drive disclosed in my copending application Serial No. 149,343, filed June 21, 1937. In other aspects, however, the particular rubber roll power drive herein shown is specifically involved in the present type action invention.

The rubber-covered roller 22 is suitably journaled in the machine frame and is preferably continuously rotated in the direction of the arrow in Fig. 1. The devices actuated by the rubber roller 22 are in the form of bell crank levers or rockers 23 and 24 pivotally mounted in rows on the cross bars 13 and 14 on pivot rods 20 25 and 26. Each of the bell crank levers is loosely positioned in a slot in its respective cross bar so as to be guided in its pivotal movement and a stop or series of stops 27 is related to the cross bars to determine the normal positions of 25 the bell crank levers or actuators 23 and 24. The stops 27 are preferably of rubber or some sound-deadening material.

Each of the bell crank levers 23—24 has at its lower end a cam 30 mounted for rotation 30 on a pin 31 extending laterally from the lever. When the bell crank levers are in position against the stops 27 the cams are held slightly out of engagement with the drive roll, as shown in Fig. 2 of the drawings. When any key lever 35 is depressed against the action of its return spring 32 its corresponding or related cam 30 engages the drive roller and is turned thereby the major part of a complete revolution. The mechanism for carrying out this action will now be described.

The cam 30, commencing at a low portion normally occupying a position adjacent the surface of the drive roller, is serrated as indicated at 33 around its periphery as it gradually builds up to a high point 34. The cam is held with its low point opposite the drive roller by a latch member 35 pivoted on a stud 36 which projects laterally from the lower arm of the bell crank lever. This latch is operatively associated with 50 a cam control finger 37 which acts upon a pin 38 extending laterally from the cam 30.

A spring 40 is coiled around the stud 36 and has one end fixed to a lug 41 which is integral with the cam control finger 37, and its other 55

end is fixed in a lug 42 which is integral with the latch 35. The spring tends to urge the latch and the cam control finger toward each other.

The lug 42 of latch 35, when in its normal latching position, is directly under a lip 43 of a latch-operating member 44 pivoted on the key lever at 45 and held by a spring 46 against one or the other of the cross bars 13 or 14 as the case may be. The latch-operating members play 10 in slots at the inner sides of the bars and their normal positions are determined by the inner ends of the slots and the springs 46 each of which has one end fixed to the latch-operating member and the other end fixed to a lug on an 15 associated key lever.

When a key lever is depressed its latch-operating member is moved downwardly against lug 42 which rotates the latch 35 out of engagement with a pin 50 extending laterally from the cam 30. 20 This pin is on the opposite side of the cam from the pin 38 and as the cam is released for rotation by movement of the latch 35 spring 40 acting on pin 38 gives the cam a short initial rotation which turns a higher portion of the serrated cam 25 edge into engagement with the continuously rotating power-drive roller which thereupon picks up the cam frictionally and rotates it until its extreme high point 34 passes beyond the roller. During the latter part of this action the pin 38 30 acting upon the latch control finger is stressing spring 40 to restore latch 35 to a position where it will intercept pin 50 when the rotation of the cam is complete. After the high point 34 of the cam has passed from the influence of the drive 35 roller the spring-pressed latch control finger 37 acts upon pin 38 extending from the cam 30 to complete the rotation and reengage pin 50 with the latch 35.

The operation just described causes a short 40 pivotal movement of the associated bell crank lever or actuator which is transmitted to the type bar in a manner now to be described.

For convenience of arrangement and assembly the actuator bell crank levers are arranged in 45 two rows on opposite sides of the drive roller on the cross bars 13 and 14. The transmission connections from the actuating levers 23 and 24 are all arranged in spaced slots in the cross bar 14. These consist of sub-levers 51 of bell crank shape 50 pivoted on rod 26 and having their lower arms 52 yoked at the end around pins 53 extending laterally from the upper arms of actuator levers 23 and 24. The upper arms of the sub-levers 52 have a link connection 54 with short arms 55 of 55 type bar levers 56 which latter are pivoted on the usual fulcrum wire 57 of a conventional type bar segment (not shown). Return springs 58 extending from the sub-levers to a part fixed to the frame tend to maintain the pivot points of links 54 and pivot rod 26 in alignment, thus effecting a straightened toggle for each type action. Each link 56 has a tail 60 adapted to strike against a lug 61 extending from the upper arm of sub-lever 51 to prevent the toggle from passing over dead 60 center under the influence of spring 58.

As any one of the actuator levers 23 or 24 is moved by the engagement of its associated cam with the drive roller, its related sub-lever 51 is moved pivotally to throw its upper arm forwardly 70 to break the toggle and move the type bar 56 around its pivot point 57. It will be obvious that as the toggle is breaking from its straightened position there will result an initial application of considerable force to overcome the inertia of the

parts and this will be followed by progressive acceleration of movement of the type bar to the printing point. The reverse of this action will take place on the return of the type bar under the influence of spring 58 and accordingly the 5 type bars in their final return movement will settle easily to rest against a support, not shown in the drawings, and be substantially locked against rebound by the straightening of the toggle consisting of the upper arm of sub-lever 51 and link 54.

As the drive roller 22 rotates cam 30 the corresponding actuator lever has its lower arm moved outwardly to disengage lug 42 from the latch-operating member 44 and when so disengaged, spring 40, as previously stated, acts to bias latch 35 back into latching relation with the cam 30. This, of course, lifts lug 42 slightly so that there can be no subsequent unlatching of the cam until the depressed key lever 19 has been 20 permitted to return to its normal position. Thus unintended repeat operations of the actuator type bar are prevented.

What is claimed is:

1. In a power driven typewriter, an array of 25 type actions and operating means therefor comprising, a rotating cylinder, comb-slotted mounting means for pivotally movable parts, rocker actuators in said mounting means at opposite sides of the cylinder, a line of sub-levers in spaced arrangement on the mounting means and connected for operation by the actuators, means connecting the sub-levers to the type actions respectively, a single lobe cam rotatably mounted on each actuator and adapted to be engaged with and rotated by said cylinder, means for normally preventing rotation of the cam and insuring its complete rotation when desired, said means comprising a pivot, a latch on said pivot, an operating finger on said pivot, and a spring between the latch and the finger normally tending to bias the latch into effective position to hold the cam against rotation and to bias the finger into position to rotate the cam initially into engagement with said cylinder when the latch is released and complete the rotation of the cam to latching position at the end of its engagement with said cylinder, and key operated means adapted to release the latch and effective to transmit pressure by said spring to said operating finger.

2. In a power driven typewriter, an array of 45 type actions and operating means therefor comprising, a rotating cylinder, mounting means, actuators on said mounting means, type bars, connections from said type bars to said actuators, a single lobe cam rotatably mounted on each actuator and adapted to be engaged with and rotated by said cylinder, means for normally preventing rotation of the cam and insuring its complete 50 rotation when desired, said means comprising a pivot, a latch on said pivot, an operating finger on said pivot, and a spring between the latch and the finger normally tending to bias the latch into effective position to hold the cam against rotation and to bias the finger into position to rotate the cam initially into engagement with said cylinder when the latch is released and complete the rotation of the cam to latching position at the 55 end of its engagement with said cylinder, and key-operated means adapted to release the latch and effective to transmit pressure by said spring to said operating finger.

RUSSELL G. THOMPSON.
